UNITED STATES PATENT OFFICE.

JAMES W. SLOSS, OF BIRMINGHAM, ALABAMA.

CALCULATING-MACHINE.

SPECIFICATION forming part of Letters Patent No. 694,897, dated March 4, 1902.

Application filed December 27, 1901. Serial No. 87,421. (No model.)

To all whom it may concern:

Be it known that I, JAMES W. SLOSS, a citizen of the United States, residing at Birmingham, in the county of Jefferson and State of Alabama, have invented certain new and useful Improvements in Calculating-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to such calculating-machines as, by the manipulation of keys and one or more levers, print the desired figures and calculate and print the sum of those figures. In machines of this class when one or more figures in any of the left-hand columns is printed the spaces to the right of such figures are occupied by ciphers through to the units-place.

My improvement enables the operator to use one or more left-hand columns or rows of keys for printing dates or numbers and the remaining columns for putting down amounts, eliminating ciphers or other figures between said columns of dates or numbers and of amounts, and to print the sum of the amounts without printing the sum of the dates or numbers, and yet to permit all the rows or columns to be used for amounts, if desired.

The accompanying drawings illustrate the invention, Figure 1 being a side elevation and showing some of the adjacent parts, and Fig. 2 a rear or edge view of the device. Fig. 3 is an edge view of a series of triggers in use in calculating-machines illustrated in the patent mentioned below.

Like letters of reference denote corresponding parts in the different views.

The invention is illustrated in connection with a Burrough's calculating-machine patented September 12, 1893, numbered 505,078, and applies to all the triggers on the left of the one operating to record the unit figure. In views numbered 3 and 4 of that patent the triggers numbered 717, corresponding to the part lettered D in my drawings, have each

“a laterally-extended lug d' arranged a short

distance in advance of a heel or lip d² of the next adjacent trigger, so that when any one trigger is drawn back its lug d' will after a limited movement strike the heel d² of the next trigger on the right and also swing it 55 backward, and so on, the movement being imparted from one figure to the next until all of the triggers at the right of the one directly operated have acted to release the adjacent drivers, whereby all of the said type-carrying ciphers are struck and the ciphers printed at the right of the figure or figures set in position by the operation of the keys.” I make the part of this trigger which I have lettered d³ undivided into prongs and in or 65 approximately in the same plane as the body of the trigger, so that when a trigger is swung back it will act independently and will not engage an adjacent trigger on the right or left, on which account the figure struck will 70 stand alone and other figures may or may not be thrown into position either in the next figure-space in the line or after an intervening space, and no ciphers or figures will be printed in said intervening space unless keys 75 are struck for that purpose. I also produce the same result by omitting the heel d², since the function of that heel is to engage the lug d' on the adjacent trigger, and of course the same result is secured by omitting both the 80 heel and the lug, including more or less of the entire part lettered d³ in my drawings.

The trigger D is made with a varying outline in different machines, being adapted by notches, catches, or otherwise to engage other 85 parts which it actuates or by which it is actuated, and I do not limit myself to the precise form shown or to any particular form of the trigger in profile or side view, but make it throughout in approximately the same plane 90 or so that when sprung it does not engage the adjacent trigger.

What I claim and desire to secure is—

1. In combination with the retractor and the striker of a calculating-machine a trigger, located to operate in any space to the left of the units-column, and having its part d³ undivided and approximately in the same plane as the body of the trigger, for the purpose specified.

2. In the recording mechanism of a calculating-machine, having a retractor for drawing back the striker and a trigger for releasing the striker, the said trigger located to the left of any other trigger, and adapted to act independently of the adjacent trigger on its right, as herein set forth.

In testimony whereof I affix my signature in presence of two witnesses.

JAMES W. SLOSS.
